W. DIETZEL.
COMBINATION UTENSIL.
APPLICATION FILED OCT. 27, 1919.

1,353,222.

Patented Sept. 21, 1920.

UNITED STATES PATENT OFFICE.

WILLIAM DIETZEL, OF MERRICK, NEW YORK.

COMBINATION UTENSIL.

1,353,222.

Specification of Letters Patent. Patented Sept. 21, 1920.

Application filed October 27, 1919. Serial No. 333,819.

To all whom it may concern:

Be it known that I, WILLIAM DIETZEL, a citizen of the United States, residing at Merrick, in the county of Suffolk and State 5 of New York, have invented certain new and useful Improvements in Combination Utensils, of which the following is a specification.

This invention relates to combination utensils, and has for its main object the provision of such a device which may be used either as a table brush or broom, or again as a combination table brush and refuse or crumb pan.

15 Another object of my invention is to provide a combination table brush and crumb or refuse pan having a suitable mechanism connecting the two so that they are inseparable from each other and so that they may 20 be interlocked mutually to provide a single unit brush or broom.

Although I have mentioned my device as useful as a table brush and pan, I do not wish to limit myself to such use, as it may 25 well be applied to a floor broom and dust pan by simply constructing the various parts of sufficient size.

The above and other objects will become apparent in the description below, in which 30 characters of reference refer to like-named parts in the drawings.

Referring briefly to the drawings, Figure 1 represents my device in front elevation, showing the same when ready for use as a brush.

Fig. 2 is a side view of the same showing the parts in position for use as a combination brush and pan.

Fig. 3 is a partial rear view of the device of Fig. 1.

Fig. 4 is an elevational view of the brush frame.

Fig. 5 is a lower view of the same with a brushing means attached.

45 Fig. 6 is a cross-sectional view taken substantially on the line 6—6 of Fig. 1.

Fig. 7 is a cross-sectional view taken substantially on the line 7—7 of Fig. 1.

Referring now in detail to the drawings, 50 the numeral 1 represents the handle of the device, and 2 represents a stamped rib there-in to strengthen the same. A pan 3, constructed in the usual manner, is rigid to said handle at an inclination thereto, as is ap- 55 parent in Fig. 2. Said pan has also a rib

4 therein to strengthen the same. The handle 1 has a longitudinal slot 6 on each side, and is preferably of hollow construction. A bent wire rod 5, bent substantially in the form of a closed U, has its bridge in engagement with said slots 6, and its ends in engagement with the brush member 8. The member 8 is for this purpose provided with a pressed out recess 7 so as to provide a free strip 7a about which the ends of said 60 rod 5 are bent so as to secure the same thereto, and at the same time to provide a pivot about which said brush member may be turned.

As aforementioned, the brush member 8 70 is adapted to be folded, co-operatively with its handle 13, in the direction of the arrow in Fig. 2 into the closed or unitary position shown in Fig. 1. In order that the brush member may be securely retained when 75 in the closed position, spring clips or catches 11 are stamped out of the same at 11, and these clips engage the edge of the pan 3 and securely hold thereon, thus preventing slipping of the brush member therefrom. I have 80 illustrated one form of brush, although any convenient form may be used without departing from the spirit of my invention. This form comprises a strip of cloth or felt 85 secured to the member 8 by weaving the same between teeth 10 stamped out alter-nately in opposite directions from the bottom edge of the member 8. At the same time that the clips 11 engage the pan, the handle 13 of the brush member 8 passes 90 into the recess or hole 14 in the upper por-tion of the pan 3, as illustrated in Figs. 1 and 3, where it is securely retained by the resiliency of the metal.

Now in use, my device may be used either 95 as a single brush or broom, as in Fig. 1, whence it acts as a single integral and rigid device, since its separate parts are all rigidly interlocked. When used as a com-bined brush and pan, as in Fig. 2, the mem-100 ber 13 is moved, in broom fashion, back and forth on its pivot, and the refuse is thus passed onto the pan 3. This combination affords a convenient co-operative device which may readily be carried about as a sin-105 gle unit, and which makes impossible the separation of the brush from the pan, so that the two are at all times at hand and ready for service.

Having thus described my invention, what 110

I claim and desire to secure by Letters Patent is as follows:

1. A combination brush and pan, and pivotal means connecting said brush with said pan, said means comprising a slot in said pan, said slot extending laterally through the handle of said pan, an eyelet or hole in said brush, and means engaging said eyelet or hole and slidably engaging said slot, and means for rigidly binding said brush and pan in a single unit comprising resilient clasps on said brush adapted to catch said pan.
2. A combination brush and pan comprising said brush and pan and means for pivotally connecting the same together, said means comprising a slot in the handle of said pan, said slot extending laterally through said handle, an eyelet or hole in said brush, a bent rod engaging said eyelet or hole and slidably engaging said slot, and means for rigidly binding said brush

and pan in a single unit comprising resilient clasps on said brush adapted to catch said pan.

3. A combination brush and pan comprising said brush and pan and means for pivotally connecting said brush and pan together, and means for rigidly binding said brush and pan in a single unit comprising resilient clasps on said brush adapted to catch said pan.

4. A combination brush and pan comprising said brush and pan and means for pivotally connecting said brush and pan together, and means for rigidly binding said brush and pan in a single unit comprising resilient clasps on said brush adapted to engage the edge of said pan, and a recess in said pan adapted to receive the handle of said brush.

In testimony whereof I affix my signature.

WILLIAM DIETZEL.
